ORNAMENTED FABRIC AND METHOD OF AND APPARATUS FOR ORNAMENTATION.

Application filed February 17, 1925, Serial No. 9,839, and in Austria January 27, 1925.

This invention relates to ornamented fabrics and to the method of as well as to an apparatus for ornamentation.

It has been known to decorate or ornament fabrics, such as gauze, silk or the like, by applying thereto drops or globules of gum-arabic or like materials. Furthermore it has been proposed to use as material to be applied the condensation products of phenol and formaldehyde in order to obtain ornaments unaffected by heat and moisture, for which purpose the said material is arranged in pattern effect on the fabric at an intermediate stage of the chemical reaction between phenol and formaldehyde, during which the mass is still liquid or at least plastic, and is thereafter on the fabric rendered insoluble and infusible.

According to the present invention the fabric is ornamented by means of a material, which consists of the final products of the reaction between a urea or its derivatives on the one hand and of aldehydes, especially formaldehyde on the other.

The reaction between urea or its derivatives and formaldehyde takes place in three stages. First of all water-soluble initial products are formed, which at ordinary temperature or when heated gradually assume an increased viscosity. At a given moment these initial products set by gelatinization to a semi-liquid intermediate product, which is less soluble in water. Finally, when allowed to stand at ordinary temperature or when heated the gelatinized masses are transformed into hard final products, insoluble in water. The hard artificial masses thus obtained are glass-like, of great beauty and stability.

For ornamenting the fabric a condensation product of this kind is employed while in one of the intermediate stages of the chemical reaction resulting in the formation of the hard final product. If in some manner drops or little globules, or deposits in general of such condensation products are applied to a fabric, these deposits will after some time change to the state of the hard insoluble final product. By applying heat this transformation may be considerably accelerated.

The final product, in contradistinction to that of the reaction between phenol and formaldehyde, is perfectly colourless and has the aspect of rock crystal. Therefrom

the important advantage results, that the ornaments can be made perfectly transparent and colourless or to show the most delicate shades of any tint. Also fluorescent effects can be obtained, which is not the case with the condensation products of phenol and formaldehyde. In so far as resistance to heat and moisture are concerned, these final products are not substantially inferior to the condensation products of phenol and formaldehyde, their hardness being the same.

In the following some steps, measures and means for carrying the invention into practice are described, which may just as well be employed for applying to fabrics and the like any other liquid or semi-liquid material, capable of subsequently hardening, for the purpose of decorating or ornamenting the fabrics.

In the accompanying drawing Fig. 1 is a perspective view of a machine for producing the ornaments, Figs. 2 to 5 are sectional elevations of the device for applying the mass to the fabric, showing different positions of its parts, and Fig. 6 shows by a diagrammatical way the principle on which the working of the machine is based.

This principle consists of pushing a needlelike utensil 1 (Fig. 6) through the fabric 2 on those places or points thereof where the ornament is intended to be fixed, thereafter applying a drop of the mass, to be used for producing the decoration, to its point and finally withdrawing it from the fabric. Applying the drop to the needle's point can most simply be effected by dipping the needle into a receptacle containing the liquid or semi-liquid mass. When the immersed needle is withdrawn from the mass, a drop 3 of the latter will remain adherent to its point and the greatest part of the mass of said drop 3 will be stripped off so as to be pressed against the underside of the fabric 2, when the needle is entirely pulled out of the latter. Some small amount of the material will remain adherent to the needle and will be stripped off by the upper side of the fabric, when the latter is pierced the next time by the needle. But even if no liquid remains adherent to the needle, when pulled out, a small amount of the mass forming the drop will pass on through the hole to the upper surface of the fabric. This smaller part will form a flat little drop 4 on the upper surface, which upper drop is

bodily connected to the drop 3 by a neck filling the hole. If the mass thus applied is allowed to dry at approximately horizontal position of the fabric, the drop 3 will 5 in hardening preserve its spherical form, as gravity tends to pull its mass downward. On the other hand the little drop 4 on the upper surface of the fabric will, owing to the effect of gravity flatten and will assume 10 the form of a flat rivet-head, connected to the spheric drop 3 by a neck or web 5 which fills up the hole in the fabric. The fixing of the drop constituting the ornament by means of a rivet-head is of course much more 15 reliable and effective than that resulting from hitherto known methods, in which the material employed for the ornament was not self-sealed on both sides of the fabric by piercing such as described above, but applied to its upper surface only.

An essential difference of the new method as compared with those hitherto known, consists also in the form of the ornaments obtained thereby. Whilst with the known 25 methods only flattened deposits can be obtained, the present method produces a spherical form, like that of beads, so that the general aspect is similar to that of beads sewn on the fabric.

30 The most essential condition for obtaining deposits of globular shape is to let the hardening of the mass take place at such position of the fabric, that the deposits are hanging on its lower surface, that is to say at a position either exactly or approximately horizontal, so that gravity pulls the material in a direction approximately perpendicular to the surface of the fabric and keeps it tensioned in such direction. If this essential 35 condition is fulfilled, globular deposits may be obtained even if semi-liquid deposits are applied to the fabric in the hitherto known manner by downward movement from above.

The above explained principle may be carried 40 into effect by various modes, one of which is by way of example illustrated by the accompanying drawing. Here the fabric 2 to be decorated is spread between two bars 6 by attaching its lateral rims or pins 7 of 45 the bars. The latter are supported by the frame 10 and guided by recesses 8 of rails 9, which are forming part of the frame. Means are provided for lengthwise moving at a given moment both bars simultaneously, for 50 instance by turning the handle 11 of a rope-drum 12, the ropes 13 of which are at 14 fastened to the bars 6.

The device for applying the ornamentation 55 to the fabric is mounted in a frame 15, which is guided by rods 16 in bearings 17 so as to be vertically shiftable. Lifting and lowering of this frame 15 can be effected by means of a lever 18, the slot 19 of which engages with a bolt 20 screwed into the rod 16.

60 Within the frame 15 there is a second smaller

frame 21, provided with a perforated bottom 22. By means of screws 29 this second frame can be adjusted and fixed within the former. The perforations of the bottom 22 may either be arranged so as to form the 70 pattern to be produced or they may be uniformly distributed all over the surface of the bottom plate, in which latter case the same bottom can be used for making various patterns. To the lower surface of the bottom 22 rails 32 are secured for a purpose to be explained further on. Within the frame 21 a third frame 23 is provided, which has also a perforated bottom plate 24, the 75 perforations of the latter being arranged so as to correspond exactly to those of the bottom plate 22. The frame 23 is vertically movable within the frame 21 and is, for assuring exact movement, guided by pins 25, which are rigidly fastened to the bottom of frame 21. For lifting up and lowering it serves a fourth frame 28 having only three sides, two of which form handles at their front ends. These side bars bear pins 27, 80 engaging with slanting slots 26 of the frame 23 in such manner, that by pulling the said sidebars in one direction, the frame 23 will be lifted up and by pushing them in the other will be lowered. Below the path of the fabric a receptacle 30 is mounted, the area of which is about the same as that of the frame 23. This container 30 can be shifted vertically by means of a lever 31 and appropriate links connected thereto, and is to be filled with the liquid or plastic mass 100 to be employed for producing the ornamentation. If ornaments of various colours are to be made, the receptacle is subdivided accordingly, each division containing a mass of different colour.

105 In the illustrated example the perforations of the bottom plates 22 and 24 are arranged so as to form the pattern. In every one of these holes a needle 1 is inserted, the head 33 of which rests upon the bottom 24. A relatively heavy plate 34 laid into the frame 24 on the heads of the needles holds the latter in place.

110 The apparatus is to be operated as follows:

115 At the beginning of each working period both frames carrying the needles are kept at a certain distance from the fabric, as is shown in Fig. 2. By pressing the lever 18 downward they are lowered into the position as shown by Fig. 3, in which the lower edges of the rails 32 are placed immediately above the path of the fabric. If now the frame 23 is lowered by horizontally shifting the frame 28, the needles, which are vertically guided by the perforations of the bottom plate 22, will pierce the fabric 2. If the latter is densely woven, it will generally be necessary to support it during the time the frame 23 is descending, in order to obtain 120 125 130

that all needles will uniformly and surely penetrate. For this purpose a feltplate 36 (Fig. 4) may be used as a support or else a perforated plate, the holes of which correspond exactly to those of the two bottom-plates. After the needles have pierced the fabric, the felt plate or its substitute is removed and now the receptacle 30 is lifted up by means of the lever 31. (Fig. 5.) There-

- 10 by the points of the needles are dipped into the liquid, part of which will, when the receptacle is let down again, remain adherent to the points and will form drops. Thereafter the frame 23 is lifted so that it will 15 reassume the position according to Fig. 3. Thereby the drops adherent to the needles will be stripped off therefrom by the fabric. Also during this upward movement of the frame 23 it is necessary to keep the fabric in 20 position in order to assure that all the needles are uniformly pulled out therefrom. According to the illustrated example this is obtained by the rails 32 a sufficient number of which are secured to the bottom plate 22 25 as has been mentioned above.

The lower surface of the fabric will now carry drops arranged in the same position as was the case with the needles in the bottom plate 24. On the top surface of the fabric flat little drops have been formed, connected to the drops on the under-side, thus securing the latter to the fabric in the manner of a rivet head.

- Finally by actuating the lever 18 the frame 15 is lifted and will thus come back into its original position as shown by Fig. 2, so that the described series of operations can be repeated. But preliminary to that the fabric is by turning the handle 11, to be 40 advanced so far, that the next part thereof, to be provided with the same ornament, is placed underneath the applying device.

- During the hardening of the applied ornaments the horizontal position of the fabric is 45 to be maintained, as otherwise the drops 3 would lose their spherical form. Therefore the fabric is preferably left on the bars 6, which for the purpose of keeping them in the same distance after removal from the 50 rails 9, are to be provided with some appropriate means, such as for instance the flat rails 37, which, as work proceeds, are successively mounted on the bars by means of thumb-screws.

- 55 The fabric to be ornamented may be of any character suitable for the intended purpose, such as for instance woven, knitted, netted, felted or leather fabric.

- In the following claims I use the term 60 "urea" not only to include carbamide, but also thio-urea and substitution products of urea or of thio-urea.

What I claim is:

1. The method of ornamenting fabrics, which consists in placing in contact with the

fabric spaced liquid or semi-liquid deposits of an intermediate reaction product of a urea and of an aldehyde having the property of forming a clear hard solid, forming upon each deposit a neck extending through the fabric and a rivet-head upon the neck that secures the deposit to the fabric, and then transforming the deposits into the hard final product.

2. The method of ornamenting fabrics which consists in applying deposits of a liquid or semi-liquid material to the lower face of a fabric in spaced relation to each other, supporting the fabric in a stretched condition for advancement to different positions in a horizontal plane, and hardening the deposits while the fabric is supported in the horizontal plane with the deposits hanging from the lower face of the fabric.

3. The method of ornamenting fabrics 85 which consists in piercing the horizontally spread fabric by means of a needle on those points which are to receive an ornament, dipping the needle into the mass constituted by the liquid or plastic intermediate 90 products of the reaction between a urea and aldehydes, and thereafter pulling the needle out of the fabric, whereby the drop remaining adherent to the needle after withdrawal from said mass will be stripped off by the 95 fabric to form hard, insoluble, glass-like deposits.

4. The method of ornamenting fabrics which consists in piercing the horizontally 100 spread fabric by means of a needle on those points which are to receive an ornament, dipping the needle into a mass constituted by the liquid or plastic intermediate products of the reaction between a urea and aldehydes, thereafter pulling the needle out of the 105 fabric, whereby the drop remaining adherent to the needle after withdrawal from said mass will be stripped off by the fabric, and reducing the deposited mass into the 110 state of the hard final product at horizontal position of the fabric.

5. The method of ornamenting fabrics which consists in supporting the lower surface of the horizontally spread fabric on such places which will not receive an ornament, piercing the horizontally spread fabric by means of a needle at those points which are to receive an ornament, dipping the needle into a mass constituted by the liquid or plastic intermediate products of the reaction between a urea and aldehydes, pulling the needle out of the fabric, whereby the drop remaining adherent to the needle after withdrawal from said mass will be stripped off by the fabric, and transforming the deposited mass into the hard final product at horizontal position of the fabric with the drops hanging on its lower surface.

6. The method of ornamenting fabrics 125 which consists in supporting the lower sur-

- face of the horizontally spread fabric on such places which will not receive an ornament, piercing the horizontally spread fabric by means of a needle at those points 5 which are to receive an ornament, dipping the needle into a mass constituted by the liquid or plastic intermediate products of the reaction between a urea and aldehydes, supporting the fabric also from above, pulling 10 the needle out of the fabric, whereby the drop remaining adherent to the needle after withdrawal from said mass will be stripped off by the fabric, and transforming the deposited mass into the hard final product at 15 horizontal position of the fabric with the drops hanging on its lower surface.
7. Apparatus for ornamenting fabrics, consisting of means for supporting a fabric to be ornamented in a horizontally spreading 20 condition and so that it may be advanced in a horizontal plane while its spreading condition is maintained, a needle carrier, and means for lifting and lowering the needle carrier to cause the needles to project thru 25 the spreading fabric.
8. Apparatus for ornamenting fabrics, consisting of means for supporting a fabric to be ornamented in a horizontally spreading 30 condition and so that it may be advanced in a horizontal plane while its spreading condition is maintained, a frame with a perforated bottom, needles carried by said frame and having heads resting upon said bottom, and means for lifting and lowering 35 the frame to cause the needles to project thru the spreading fabric.
9. Apparatus for ornamenting fabrics, consisting of a frame with a perforated bottom, on which the heads of needles rest, 40 a plate placed within this frame for the purpose of keeping the needles down, means for lifting and lowering the frame carrying the needles, means for horizontally spreading the fabric, and means for placing a liquid 45 or plastic substance upon the needles to be applied by the needles to the fabric.
10. Apparatus for ornamenting fabrics, consisting of a frame with a perforated bottom, on which the heads of needles rest, a 50 plate placed within this frame for the purpose of keeping the needles down, a second frame with a perforated bottom guiding the needles, means for lifting and lowering the frame carrying the needles, means for horizontally spreading the fabric, and means for presenting a liquid or plastic substance to the needles to be applied by the needles to the fabric. 55
11. Apparatus for ornamenting fabrics, consisting of a frame with a perforated bottom, on which the heads of needles rest, a plate placed within this frame for the purpose of keeping the needles down, a second frame with a perforated bottom guiding the 60 needles, means for lifting and lowering the frame carrying the needles, means for horizontally spreading the fabric, and means for presenting a liquid or plastic substance to the needles to be applied by the needles to the fabric. 65

frame carrying the needles, a third frame, in which the second frame guiding the needles is adjustably mounted, means for lifting and lowering this third frame means for horizontally spreading the fabric, and means for presenting a liquid or plastic substance to the needles to be applied by the needles to the fabric. 70

12. Apparatus for ornamenting fabrics consisting of a frame with a perforated bottom, on which the heads of needles rest, a plate placed within this frame for the purpose of keeping the needles down, a second frame with a perforated bottom guiding the needles, means for lifting and lowering the frame carrying the needles, a third frame, in which the second frame guiding the needles is adjustably mounted, means for lifting and lowering this third frame, means for horizontally spreading the fabric, an open receptacle to hold the mass to be employed for producing the ornamentation and means for lifting and lowering this receptacle. 80

13. Apparatus for ornamenting fabrics, consisting of a frame with a perforated bottom, on which the heads of needles rest, a plate placed within this frame for the purpose of keeping the needles down, a second frame with a perforated bottom guiding the needles, means for lifting and lowering the frame carrying the needles, a third frame, in which the second frame guiding the needles is adjustably mounted, means for lifting and lowering the third frame, means for horizontally spreading the fabric, an open receptacle subdivided by partitions, and means for lifting and lowering this receptacle. 90

14. Apparatus for ornamenting fabrics, consisting of a frame with a perforated bottom, on which the heads of needles rest, a plate placed within this frame for the purpose of keeping the needles down, a second frame with a perforated bottom guiding the needles, means for lifting and lowering the frame carrying the needles, a third frame, in which the second frame guiding the needles is adjustably mounted, means for lifting and lowering the third frame, an open receptacle subdivided by partitions, means for lifting and lowering this receptacle, means for horizontally spreading the fabric and means for advancing the latter at intervals. 100

15. As a new article of manufacture, a pliable fabric ornamented by separate hard deposits having a globular form at one face of the fabric, an integral neck extending through an aperture in the fabric and a rivet-head at the opposite face of the fabric and formed of a material applied to the fabric in a liquid or semi-liquid condition. 110

16. As a new article of manufacture, a pliable fabric ornamented by separate hard deposits having a globular form at one face of the fabric, an integral neck extending through an aperture in the fabric and a rivet-head at the opposite face of the fabric and formed of a material applied to the fabric in a liquid or semi-liquid condition. 120

et-head at the opposite face of the fabric and formed of a condensation material applied to the fabric prior to the formation of said neck and rivet-head.

5 17. As a new article of manufacture, a pliable fabric ornamented by spaced hard insoluble deposits of the final condensation product obtained by the reaction between a urea and formaldehyde, which deposits are 10 of globular form.

18. As a new article of manufacture, a

pliable fabric ornamented by separate hard deposits having a globular form at one face of the fabric, an integral neck extending through the aperture in the fabric and a 15 rivet-head at the opposite face of the fabric and formed of the condensation product obtained by the reaction between a urea and formaldehyde.

In testimony whereof I have affixed my 20 signature.

JOSEF CHALOUPKA.
